GATE OPERATING MEANS

Frank A. Duffe, Wilton Junction, Iowa

Application September 8, 1938, Serial No. 229,030

1 Claim. (Cl. 39—39)

This invention relates to a gate operating means, and it is an object of the invention to provide a means of this kind which can be readily operated upon approaching the gate from either side to swing the same into open position or to move the same into closed position after passing through the gateway together with means assuring the locking of the gate when in fully closed position.

The invention consists in details of construction and in the combination and arrangement of the several parts of my improved gate operating means whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is an elevational view of gate operating means constructed in accordance with an embodiment of my invention, the gate being in closed position;

Figure 2 is a view in top plan of the structure as illustrated in Figure 1, a second position of certain of the parts being indicated by broken lines;

Figure 3 is an enlarged fragmentary elevational view illustrating a portion of the operating means in an adjustment when the gate is in a partially closed position;

Figure 4 is a fragmentary sectional view taken substantially on the line 4—4 of Figure 3;

Figure 5 is a fragmentary elevational view of the latch post and a portion of the closed gate;

Figure 6 is a detailed sectional view taken substantially on the line 6—6 of Figure 1;

Figure 7 is a fragmentary view in perspective of one end portion of the elbow member as herein embodied;

Figure 8 is a fragmentary view in perspective of the opposite end portion of said elbow member as herein comprised.

As disclosed in the accompanying drawings, I indicates a gate post having hung thereon, as at 2, in a conventional manner a swinging gate G, the free end portion of which coacts with the latch post 3. The post 3 has suitably secured thereto, as by the removable screws 4 or the like, a keeper 5 with which is adapted to coact the locking latch 6. This latch 6 as herein disclosed

constitutes an angular or crank-like extremity of an elongated rod 7.

This rod 7 is rotatably supported adjacent to the outer end of the gate G by a bearing 8 extending outwardly from a leg 9 of a bracket 10. As herein disclosed and as particularly illustrated in Figure 6, this bracket 10 is in the form of an inverted U and straddles from above one of the horizontally disposed bars 11 comprised in the structure of the gate G. The second leg 12 of the bracket 10 has threaded therethrough a holding or binding screw 14 for clamping the bracket 10 in position upon the bar 11. This particular construction and mounting of the bracket 10 allows the same to be raised or lowered as may be required to assure the most effective positioning of the latch 6 for coaction with the keeper 5.

The rod 7 extends substantially the entire length of the gate G and at the hinge end portion of the gate G the rod 7 is rotatably supported by a vertically disposed bar 15 comprised in the structure of the gate G. This end portion of the rod 7 may, however, be otherwise mounted as preferred.

The inner end portion of the rod 7, or that end portion adjacent to the hinge end of the gate G, carries an outwardly and laterally directed rock arm 16 of desired length. As herein disclosed the free end portion of this arm 16 is formed to provide an eye member 17 which freely interlocks with an eye member 18 carried by an end portion of a substantially rigid elongated arm or link 19. The opposite end portion of the arm or link 19 is pivotally connected, as at 20, with an end portion of a latch bar 21.

This latch bar 21 is pivotally connected, as at 22, at a point slightly to one side of its longitudinal center to an elongated operating member or bar 23.

In the present embodiment of my invention this latch member or bar 23 is flat with its flattened faces vertically disposed except at one end thereof where the member or bar 23 is quarter turned, as at 24, for pivotal connection, as at 25, with the outer portion of an elbow member 26 carried by the gate G and extending outwardly and laterally from a side of the gate.

As herein disclosed this elbow member 26 is formed of an angle rail and at one end portion this elbow member 26 has a flange continued by a lug 27 with which coacts a U-clamping member 28, said member being also in engagement with the adjacent end vertical bar 29 comprised in the structure of the gate G. The op-

posite end portion of the elbow member 26 is formed to provide an upstanding lug 30 securely held by a U-shaped clamp 31 to a securing bar 32. This lug 30 is formed by striking up an end portion of one of the flanges *a* of the elbow member 26 and the adjacent end portion *b* overlies the securing bar 32 and is held to such bar by the U-clamp 33. The bar 32 is securely held to the gate G and in a vertical position by the U-clamps 34 and 35. The U-clamp 34, as herein disclosed, straddles the upper portion of the bar 32 and the adjacent upper horizontal member 11 of the gate structure. The lower clamp 35 straddles the lower horizontal member 11 and is secured to the bar 32.

By the use of the clamps 34 and 35 the bar 32 may be readily placed as desired upon the structure of the gate G and the U-clamps 31 and 33 permit a selective adjustment of the connection of the elbow member 26 with said bar 32. The clamping members 28 also permit a similar selective adjustment of the outer end of this elbow member 26.

An end portion of the operating member or bar 23 laps a rock lever 36 and at a desired distance inwardly of its outer or free end the member or bar 23 is pivotally connected, as at 37, to the lever 36 at a point substantially central of said lever. This rock lever 36 at one end portion is pivotally connected, as at 38, to a post 39 or its equivalent positioned to one side of the post 1 and substantially in alignment with the posts 1 and 3.

The outer or free end portion of the lever 36 has suitably anchored thereto, as at 40, a flexible member 41 which is continued by the separate flexible members 42. These members 42 are disposed over suitably supported pulleys 43 comprised in the pulley frame 44 depending from a supporting arm 45 carried by the upper portion 40 of the post 39. These flexible members 42 lead to the guide pulleys 46 carried by the upper portions of the posts 47 at opposite sides of the gate post 1 and at predetermined distances removed therefrom. The free extremity of each of the members 42 can be readily grasped by the occupant of a vehicle approaching the gate from either direction to throw the lever 36 to open the gate or to close the gate.

When the gate G is fully closed the lever 36 extends in a general direction toward the post 1 and when the gate is in its fully open position, this lever 36 is oppositely disposed or directed as generally indicated by dotted lines in Figure 2.

When the gate is fully closed upon initial raising of the lever 36, the latch bar 21 allows the rod 7 to rock in a direction to release the latch 6 from the keeper 5 so that the gate G may be swung into open position. As the gate G is swung into closed position the lever 36 will contact with the adjacent end portion of the latch bar 21 and rock the same in a direction to impose pull upon the rock arm 19 of the rod 7 to throw the latch 6 into locking engagement with the keeper 5 and to maintain the latch in such position until such time when the lever 36 is again raised or swung upwardly.

The member or bar 23 and the elbow member 26 are operatively engaged by a retractile member 48, herein disclosed as a conventional coil spring, which serves to prevent the gate from stopping at an intermediate position as it will be obvious that the latch bar or member 23 will at all times have a pull exerted thereon.

From the foregoing description it is thought to be obvious that a gate operating means constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

In combination with a swinging gate and a rocking latch carried thereby, a rock lever, an operating member operatively engaged with the gate and pivotally connected to the rock lever, means for swinging the rock lever to open or close the gate, a latch bar pivotally mounted on the operating member, an operative connection between the latch bar and the rocking latch for swinging the latch into released position upon swinging movement of the latch bar in one direction, the rock lever contacting with the latch bar upon closing of the gate to swing said latch bar in a direction to swing the latch into locking position, and means for vertically adjusting the latch and holding the same in selective adjusted position.

FRANK A. DUFFE.
